UNITED STATES PATENT OFFICE

KNUT W. CARLGREN, OF SALT LAKE CITY, UTAH.

PIPE-COUPING.

No. 895,617.

Specification of Letters Patent.

Patented Aug. 11, 1908.

Application filed December 9, 1907. Serial No. 405,831.

To all whom it may concern:

Be it known that I, KNUT W. CARLGREN, a citizen of the United States, residing at Salt Lake City, in the county of Salt Lake and State of Utah, have invented certain new and useful Improvements in Pipe-Couplings, of which the following is a specification.

This invention is designed to obviate the slow and dangerous operation of coupling 10 the steam and air pipes in railway air brakes. The coupling works automatically and connects the fluid pipes at the moment the cars are coupled, and automatically disconnects the pipes, when the cars are uncoupled. 15 The device is adapted to be applied to the standard air or steam pipes now in use, and with comparatively small cost.

The accompanying drawings illustrate the invention, in which 20 Figure 1 is a reduced side view, in operative position attached to the under sides of two contiguous cars, which are shown fragmentarily. Fig. 2 is a plan view of one member of the device, the car and its coupler 25 being removed. Fig. 3 is a vertical section of a part of one member of the device. Fig. 4 is a front elevation of a coupling box. Fig. 5 is a horizontal cross section on line y—y, of Fig. 4. Fig. 6 is a rear elevation of a hanger 30 which is partly broken away to show the end of a guide and coil spring.

10 designates the bottom of a railway car, and 11 an ordinary car coupler.

12 and 13 are hangers on the car bottoms, 35 to support the pipe coupling mechanism. The two members constituting my pipe coupling system are supported beneath adjacent cars and are substantially alike, so that the description of one will apply to the 40 other, but in reversed relative position.

14 is a box, provided with a rotatable tube 15, movable in a sleeve 18, fixed on a reciprocating cross piece 23. Guide rods 24, on said piece 23, extend through apertures 25, 45 in the hanger 13. Each guide rod 24 is encircled by an extension coil spring 22, which extends from the piece 23 to the hanger 13, and, normally, forces the cross piece 23 and the sleeve 18 outwardly, until the funnel 50 formed hood 19, fixed on said sleeve, contacts with the hanger 12 at an opening, through which the hood projects. The tube 15 has a solid end 16, to which is keyed a twisted, elongated plate 26, which extends 55 through a slot 27, in the hanger 13. This construction produces a rotation of the plate

26 and tube 15, when the device is forced back into operative position and causes the curved fingers 17, 17, at the outer end of tube 15, to interlock with similar fingers on the 60 tube of the coupling on the adjoining car, and to remain interlocked, until the uncoupling of the cars permits a separation of the cars, and a contemporaneous reverse rotation of the tube 15, and the release of the 65 fingers 17.

Steam and air are provided through the usual pipes. The air cannot enter tube 15, however, when the device is not in service, because the port 31 does not then align with the pipe nipple 30. But the rotation of the tube by the impact and the coupling together of the cars, brings the port 31 around and opposite to the pipe nipple 30, and makes a continuous passage of the fluid through 75 the pipe 30, and from the tube 15, on one car, into the opposite tube on the next car, and so on through the train. Other tubes as 35, in the brake system, are opened and closed simultaneously with the tube 15, by means of 80 an arm 36, passed through a slot 37, in sleeve 18, and rigidly attached to tube 15, its outer end having a link connection 38, with a crank arm 39 attached to a rock-shaft 40, journaled in the box 14 and provided within the box 85 with valves for opening and closing the communications between the tubes 35 in both members of the device. In order to secure certain contact between the oppositely disposed tubes 15, I provide the funnel form 90 guide 19, on the sleeve 18, which, by its sliding contact with the circular opening in the hanger 12, compels an accurate alinement of the tubes 15, for positive, mutual engagement. A dowel guide 43, projects from the face of 95 each box 14, and is adapted to engage a socket 44, in the opposite box to assist in alining these parts.

What I claim and desire to secure, is—

1. In a fluid pipe coupling a supporting 100 hanger having apertures and a vertical slot therein, a rotatable tube having terminal engaging fingers, a sleeve on said tube, a reciprocating cross piece on the inner end of said sleeve, guide rods on said cross piece extending through the apertures in said hanger, expansion coiled springs on said rods and a twisted plate keyed to the inner end of said tube and extending through the slot in said hanger, for the purpose specified. 105

2. In a fluid pipe coupling a rotatable tube, a sleeve thereon having a slot therein, an

arm rigid on said tube and extending through said slot, a box on said sleeve, tubes in said box, a rock-shaft provided with valves in said box, a crank on said rock-shaft and a link connecting said crank and said arm, whereby the rotating motion of the tube rocks said shaft to open and close said valves.

3. In a pipe coupling a rotatable tube, a longitudinally reciprocating sleeve thereon, supporting hangers for said sleeve and tube, the foremost of which has a large aperture,

through which said tube and sleeve extend and a funnel form guide on said sleeve, adapted to engage said hanger at the edge of said aperture, for the purpose described.

In testimony whereof I affix my signature, in presence of two witnesses.

KNUT W. CARLGREN.
